UNITED STATES PATENT OFFICE.

HENRY HAASE, OF PHILADELPHIA, PENNSYLVANIA, ASSIGNOR TO THE HENSEL, COLLADAY COMPANY, OF PENNSYLVANIA.

DESIGN FOR A SKIRT-PROTECTOR.

SPECIFICATION forming part of Design No. 30,866, dated May 23, 1899.

Application filed April 26, 1899. Serial No. 714,588. Term of patent 14 years.

To all whom it may concern:

Be it known that I, HENRY HAASE, a citizen of the United States, residing in the city and county of Philadelphia, State of Pennsylvania, have invented and produced a new and original Design for a Skirt-Protector, of which the following is a specification, reference being had to the accompanying drawings, forming part thereof.

10 The leading feature of my design for a skirt-protector is a head having a pendent brush on the lower edge thereof, loops on the upper edge thereof, and a single row of longitudinally-striped blocks on the side face of said head along the lower end thereof adjacent to said brush.

15 Figure 1 represents a side elevation of a piece of skirt-protector embodying my design.

Fig. 2 represents a section thereof on line xx ,
Fig. 1.

20 In the drawings, A designates a piece of a skirt-protector, consisting of the head B, the brush C, pendent from the lower edge thereof, the loops D on the upper edge thereof, and a single row of longitudinally-striped blocks 25 E on the side face of the head along the lower end thereof adjacent to said brush.

Having thus described my invention, what I claim as new, and desire to secure by Letters Patent, is—

30 The design for a skirt-protector substantially as shown and described.

HENRY HAASE.
